(54) **MORTISING TIMBER**

(76) Inventor: **George Page**

George Page of Keene, New Hampshire.
Lettors Patent.

The subscriber, to the best of his knowledge, and making part of the same
containing a description in the words of the said George Page himself,
of his improvement in the machine for mortising Large Timbers.

He art knoweth that of George Page of Keene in the County of Cheshire
in the State of New Hampshire have invented a new and useful ma-
chine for mortising in large timber, and that the following is
a full and exact description of the construction and operation
of said machine as invented by me. The upper part of the ma-
chine is a cast iron box open at top and bottom, about two feet
long and seven inches wide. The sides and ends are cast separately
and fastened together by screws passing through the ends into ears
on the inside of the side pieces. Bars, also project two from each
side, quite at the end and bottom of the box, on the outside through
which is cut a female screw. Underneath each end of the box and
under the ears last described is placed a bar of iron about eleven
inches long and a half inch wide and one inch thick, through
each end of which a hole is drilled to receive a round screw on the
end of the screw which is passed through the ears above. These holes
are countersunk on the lower side and the end of the iron, head
ed. The bar rest upon the timber to be mortised, and by turning the
screws the bar can be raised or lowered, and thus the depth of the
mortise may be regulated, and by turning one or more of the screws
of the machine may be levelled or squared with the plumb staff.

At the bottom of the end pieces inside, at or near the center, ears
project the which a hole is made, and a hole is also made thro' the
bars, above mentioned, in and through which is inserted an iron
gauge which is made fast to the bar, the sharpened end of which
enters the timber and keeps the machine in its place. The sides
of the box are about three eighths of an inch thick but at the lower
end edges on the inside is a rib to give the sides greater strength.

Near the upper side, inside, are square grooves from end to end formed by projecting ribs. The ends of the box do not rise so high as the sides, by about one inch and one fourth. On the upper edge of the side pieces on the back end, extending about half the length of the box, is fastened or cast an anchor upon which play pinions hereafter mentioned. Through the sides of the box about the centre in regard to length, and near the bottom, are holes about one inch and one fourth in diameter, through which passes a round bar of iron for a windlass, from fifteen to eighteen inches long. To this bar near one end and close to the box, is attached a hatchet nail about seven inches in diameter and to the bar is fastened a hand which plays into the hatchet. On one end of this bar or windlass a chain is fastened which passes under the timber and is hooked on to the other end. The windlass is then turned by a wrench and the chain drawn around it, the hand in the hatchet holding it fast, by which means the machine is held firmly to the timber. Near the forward end and near the bottom, two iron spurs on each side piece or side iron being long are attached to the box the ends of which may be driven into the timber to aid in holding the machine fast. On each end outside one or more perpendicular bars, are drawn as guides for placing the machine without reference to the sides, another part of the machine may be called the carriage. It consists of a bottom piece of this shape: See fig. 1. of two side pieces of this shape, See fig. 11. And of an upright or end piece of this shape, See fig. 111. The edges of the bottom piece are filled to more in the grooves above mentioned in the inside of the box. The side pieces are fastened by the slants or lower edge to the bottom piece being just far enough apart to move within the box. The upright or end piece is placed at the forward end, and between the two side pieces, resting on the bottom piece at the edge of the half circles. It is well that the bottom is just sufficient to fill the interval between the side pieces, say five and a quarter inches, its height is eighteen inches, it tapers to taper at six and a quarter inches from the bottom, and is about a

and a half inches wide at top. All the edges on the back side are two inches, which at the bottom and sides are seven inches upward, project about one inch and one fourth, and then tapers and tapers until at the top the projections or ribs disappear. The side pieces are fastened to the end piece by screws which pass through the former at the places marked by dots, and through the projections or ribs. At the top and bottom of the upright pieces of an ear projecting on the fore side and perforated by a hole one inch in diameter. At about seven and a half inches above the bottom of the upright pieces on the back side are two projections, back to back, each about an inch and a quarter apart, two and a half inches long. These form the top of an inch in diameter circular cross hole passing through each longitudinal and through the upright piece in which are inserted springs which are held fast by screws inserted in the sides of the circular projections.

The bottom piece is fifteen or sixteen inches long from point to point. The side pieces about two to two and a half inches long, and at the widest end six inches, and at the centre three and a half inches wide. About three and a half inches back of the forward end of the side pieces are holes about one inch in diameter, that which passes a crank. These holes have projections outwardly resembling a hub, about three inches long, to keep the crank steady and prevent it from bending.

The hub of the crank projects about ten inches on each side of the machine, and the arms are from fifteen to eighteen inches long.

Within the machine it has the form of a common knee mill crank, the outer diameter of the crank being about three inches, the shape of the connecting lever this, see fig IV. From the arms inside (A & B) rises a shaft twenty inches long and one inch diameter, at the top it is bent forming almost a right angle and passing over the top of the upright piece and through the end of it, is a hole about half an inch in diameter. Through this hole and the holes in the two ears on the upright piece downward another shaft about one inch in diameter and two feet long and to the lower end of which is fastened a lever. This perpendicular shaft is at the shoulder at the top as to be

raised up and down by the action of the other shafts. The chair is worked by turning the crank which may be turned round or a flat way round, and back. As is most convenient, or as is considered necessary by the desired depth of the motion. On one side of the last mentioned shaft a piece of iron one fourth of an inch square and about six inches long is fastened, and also just above it a knob or button. The two springs, above mentioned, are on each side of this shaft and press against it. They have on the sides near the shaft a square notch, which receiving the piece of iron fastened to the shaft, and it is thus prevented from turning. It may be turned half round, whenever it is desirable, to face the chair the other way.

A notched pin passes through the other end of each side piece near the bottom, upon each end of which is a pinion about one and a half inch diameter which plays in the notch before mentioned. On the same side of the side pieces, are two catchet wheels, about one and a half inches in diameter. At the one end of this arbor on each side, the pinion is fitted a small crank about three inches forward of this arbor. Through projections on the top of the side pieces are holes, through which passes another arbor. This arbor opposite to each catchet wheel is, attached by screws, a hand which plays in the catchet, over seen on line. The arbor on the long side, the other on the opposite side. The notches project one inch or two from the arbor. The hands are attached to the outward ends of them, and they being so arranged, give the hands more or less play. One hand has a hook on the end and draws the other hand out and pushes the wheel round that is opposite to it, the notches in the two catchet wheels being cut so that they may be turned different ways. To give motion to the arbor and play to the hands, a small frame is made of this shape; see fig. V. The end (a) is inserted in the arbor near the end inside on the side of the arbor opposite the catchet wheel. At (b) is a leaden ball an inch in diameter. Into the end of the crank (a) a flat pin or cane is inserted, and when the crank is turned the pin is pressed against one side of the

Varies the frame which immediately falls, and by this motion they give to the plow, the carriage, moved forward or backward, as one or the other of the hands is permitted to play with, a socket which. The position and shape of the V should be such that when the plow comes, raising it by passing on one side, the shaft to which the shaft is attached shall stand exactly as much as, when it stands on the other side. While one hand is near the other should be removed, being often a pin or confined in some convenient way. A socket one and a half inches deep is made in the lower end of the perpendicular shaft, to receive the shaft of a chisel. At the upper end of this socket a hole is made transversely through the shaft to drive out the chisel.

This chisel is about seven and a quarter inches long including the handle. It is formed like a plow forming chisel except that the cutting edge on each edge (not speaking here of the cutting edge at the end) on the bevelled side, on side opposite the face, has side pieces or wings, project, which are sixteenth of an inch thick near the main part of the chisel, three eighths of an inch wide and extending up two-thirds from the cutting edge about two inches. The lower terminations of these side pieces or wings, and shaft and are made sharp by beveling the portion near the main part of the chisel on the inside and the other portion on the outside. By this mode of sharpening the side pieces or wings there is when the chisel is cutting the wood an equal pressure on the outside and inside by which they are supported and are not liable to break as when sharpened in any other way.

Operation. Having bevelled so to bore one hole where the motion is to be, the machine is then placed on the timber, the socket for chisel being regulated by a line on the timber and the perpendicular lines on the end of the machine. It is then made fast by means of the wood lags and chain, and of the dogs if necessary. The handle is then turned either counter-clockwise or past, way round and back.

If the mortise is to be a shallow one, it should be turned only a

front, way round, and back. Turning the crank direct the chisel into the timber and also moves the ruddings forward or backward, according as, round the other handles, used.

I claim as my invention the combination of the parts as above described constituting a machine for working large timber. The application and use of the several parts in a machine intended for that purpose and the mode of fastening the side pieces to wings of the chisel.
